(57) **CLAIM**

The ornamental design for nose pads for eyeglasses, sunglasses, or like eyewear, as shown and described.

DESCRIPTION

FIG. 1 is a perspective view of a pair of nose pads for eyeglasses, sunglasses, or like eyewear showing my new design in a retracted configuration;

FIG. 2 is another perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof, the right side elevation view being a mirror image;

FIG. 8 is side elevation cross-section view thereof taken along line 8-8 in FIG. 5;

FIG. 9 is a perspective view thereof shown in an extracted configuration;

FIG. 10 is an enlarged perspective view of a portion thereof indicated in FIG. 9;

FIG. 11 is an enlarged perspective isolated view of a single nose pad thereof;

FIG. 12 is an enlarged front elevation isolated view thereof;

FIG. 13 is an enlarged left side elevation isolated view thereof;

FIG. 14 is an enlarged rear elevation isolated view thereof;

FIG. 15 is an enlarged right side elevation isolated view thereof;

FIG. 16 is an enlarged top plan isolated view thereof; and,

FIG. 17 is an enlarged bottom plan isolated view thereof.

The broken lines are directed to environment and are for illustrative purposes only. The broken lines form no part of the claimed design.
